CLAIM

The ornamental design for a handle set for a golf cart, as shown and described.

DESCRIPTION

FIG. 1 is a perspective view of a handle set for a golf cart showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective schematic view illustrating a handle set showing my design disposed on a golf cart. The broken lines shown in the drawing are for illustrative purposes only and form no part of the claimed design.
